The ornamental design for a novelty duck call, as shown and described.

DESCRIPTION

FIG. 1 is a front elevational view of a novelty duck call showing my new design;

FIG. 2 is a right side elevational view thereof;

FIG. 3 is a rear elevational view thereof;

FIG. 4 is a left side elevational view thereof;

FIG. 5 is a bottom plan view thereof;

FIG. 6 is a top plan view thereof; and,

FIG. 7 is a perspective view thereof.

The surface ornamentation on the claimed design includes material covered by numerous copyrights and trademarks owned by the Walt Disney Company.
